Primary Examiner — Robert Delehanty**CLAIM**

(57) I claim the ornamental design for flushable urinary device for urinating from standing position, as shown and described.

DESCRIPTION

FIG. 1 is a perspective view of a flushable urinary device comprising a polygonal cross-section having flaps at smaller opening of the device and at larger opening of the device for being grasped by a user, male or female, when urinating through the device from standing position; a male user may direct urine from either opening of the device, but a female user may direct urine from the larger opening of the device; FIG. 2 is a perspective view of a plurality of the flushable urinary devices placed in a stack; FIG. 3 is a perspective view of a second embodiment of the flushable urinary device; and, FIG. 4 is a perspective view of a third embodiment of the flushable urinary device.
